UNITED STATES PATENT OFFICE.

HENRY SMITH, OF LISTOWEL, ONTARIO, CANADA.

TOOTH SUPPORT FOR CULTIVATORS.

Application filed December 11, 1926. Serial No. 154,141.

My invention relates to improvements in tooth supports for cultivators, and the object of the invention is to provide simple means for resiliently supporting the harrow teeth of the type disclosed in my prior Canadian Patent #126,954, dated July 12th, 1910, and as disclosed in my prior United States Patent #984,042, dated February 14th, 1911, so that the tooth will readily yield either in a lateral direction when brought into engagement with an obstruction in the field, such as a stone or root, and it consists essentially of the arrangement and construction of parts as hereinafter more particularly explained.

Fig. 1 is a perspective view of two fragmentary portions of a harrow frame and a harrow tooth and means for supporting the tooth between such portions.

Fig. 2 is a transverse section through the harrow tooth supporting means.

In the drawing like characters of reference indicate corresponding parts in each figure.

1 and 2 are two angle bar members of a harrow frame which extend parallelly and are provided with brackets 1^x and 2^x secured thereto, a bracket 1^x and 2^x being mounted on each bar 1 and 2 and provided with aligned orifices 1° and 2°.

3 is a bar extending between the members 1 and 2 and bearing against the inner face of each bracket 2^x in proximity to each end of the bar 3.

4 is a rod secured at its ends in the orifices 1° and 2° and extending freely through an orifice 3° at each end of the bar 3.

5 is a compression spring surrounding each rod 4 and extending between the bar 3 and each bracket 1^x.

6 and 7 are spacing collars driven into the end of the spring 5 and surrounding the rod 4 so as to hold the spring in spaced relation thereto.

45 The brackets 1^x are secured to the bars 1 and 2 by means of bolts 8 extending through slots 9 formed in each bar 1 and 2 so as to permit of the brackets 1^x being adjusted longitudinally of such bars to vary the compression of the springs 5.

It will thus be seen that when the harrow is drawn in the direction of arrow see Figure 1 and the tooth 10 which is supported in the usual manner by the shank 11 from the bar

55 3 strikes an obstruction such as a stone indicated at X. When such stone engages

with the inclined edge of the tooth it forces such tooth in the direction of arrow A this movement being permitted by the yielding of the bar 3 in an angular direction against 60 the pressure of the springs 5, the bar 3 being tilted during this movement, its upper edge bearing against the brackets 2^x and forming the pivotal point of the movement. Should the opposite inclined side of the tooth 10 strike the obstruction it is forced 65 in the opposite direction to that indicated by the arrow A, the lower edge of the bar 3 fulcruming on the brackets 2^x so as to provide a pivotal movement in the opposite direction to compress the springs 5. When the tooth has passed the obstruction it is forced back to its normal position by the pressure of the springs 5 bearing against 70 the bar 3.

From this description it will be seen that I have devised a very simple device which will so mount a harrow tooth of the type described that it will permit of its readily yielding movement when striking an obstruction preventing the breaking of the teeth and insuring of the tooth being carried back to its normal position after such obstruction is passed.

What I claim as my invention is:

1. The combination with two parallel members of a harrow frame, of a bracket support carried by each frame member, a bar forming a harrow tooth carrier and extending between the frame members and bearing against the bracket support, means for mounting the bar member on such bracket supports so that it will swing in either direction using its upper or lower edge as a fulcrum, and resilient means resisting such movement.

2. The combination with two parallel members of a harrow frame, of opposing brackets carried by each frame member, a rod extending between each of such opposing brackets and secured thereto, a bar member extending transversely of the harrow frame members and through the ends of which the aforesaid rod freely extends, a harrow tooth extending from the bar member, and a compression spring surrounding each rod and bearing at one end against the bar member and at the opposite end against the opposing supporting bracket remote therefrom.

110

HENRY SMITH.
